ATTORNEY.

UNITED STATES PATENT OFFICE.

EERO V. LANGEN, OF FITCHBURG, MASSACHUSETTS.

COLLAPSIBLE BOAT.

Application filed February 27, 1928. Serial No. 257,414.

This invention relates to a collapsible boat and has for its object to provide, in a manner as hereinafter set forth a boat of such class which is strong, durable, comparatively light 5 in weight, readily assembled or disassembled when desired, thoroughly efficient in its use, capable of having the elements thereof when the boat is collapsed assembled in a compact manner and occupying small space, conveniently portable when assembled and disassembled, and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood 20 that changes, variations and modifications can be resorted to which fall within the scope of the claims hereunto appended.

In the drawings wherein like reference characters denote corresponding parts throughout the several views:

Figure 1 is a top plan view of a collapsible boat in accordance with this invention with the elements of the boat in assembled position.

Figure 2 is a fragmentary view in side elevation of the boat.

Figure 3 is a plan view of the flexible body portion of the boat.

Figure 4 is a section on line 4—4 Figure 2.

Figure 5 is a side view of the keel member when extended.

Figure 6 is a bottom plan of the keel member when extended.

Figure 7 is a top plan view of a side member when extended.

Figure 8 is a side view of a side member when extended.

Figure 9 is a side view of the keel member when folded.

Figure 10 is a side view of the side member when partly folded.

Figure 11 is an end view of the central part of a side member.

Figure 12 is a top plan view of the keel member and side members arranged in a position to be folded when the boat is collapsed.

Figure 13 is an end view of the side and keel members when folded in collapsed position.

Figure 14 is a side view of the keel and side members when folded.

Figure 15 is a detail illustrating an end part of the keel member.

Figure 16 is a perspective view of one of the body tensioning devices.

Figure 17 is an elevation of the rib member when extended in a position to brace the side members.

Figure 18 is a side elevation.

Figure 19 is a top plan view of the rib member when extended.

A collapsible boat in accordance with this invention includes a flexible body portion 1, and a framing including a foldable keel member 2 formed of a series of sections hinged together, a series of foldable side members 3, 4, 5, 6, 7 and 8 and each formed of a series of sections hinged together, a series of foldable rib members 9, 10 and 11 and each formed of a series of sections hinged together, and a pair of tensioning members 12, 13 for the body portion 1.

The body portion 1 is formed of impervious material, such as canvas, is of oval-shaped contour and provided at each end with a pair of oppositely disposed triangular shaped flaps 14, 15. The pairs of flaps are oppositely disposed with respect to each other and each of the flaps of each pair is formed in proximity to a longer edge thereof with a series of spaced openings 16. The body portion 1 in proximity to its edge and between the pairs of flaps is formed with a row of spaced openings 17.

The keel member 2 includes a pair of outer sections 18, 19, a central section 20 and two pairs of intermediate sections which are interposed between the central section 20 and the outer sections 18, 19. The sections of each pair of intermediate sections are indicated at 21, 22 and the latter is of greater length than the former. The section 22 has its top edge provided in proximity to the section 21 with a groove 23. The sections 22 of the pairs of intermediate sections are hinged to the central section 20, as at 24, 25. The central section 20 has its top provided with a groove 26. The outer section 18 is hinged to one section 21, as at 27 and the outer section 19 is hinged to the other section 21 as at 28. The inner ends of the sections 18, 19 are beveled as at 29 and the outer ends of the sections 21 are beveled as at 30. The bevels 29 extend in op-

posite directions with respect to the bevels 30. Each side of each of the outer sections is rabbetted as at 31, 32 and 33. Each outer section is formed with spaced, transversely 5 extending openings 34. Each outer section is further formed with a horizontally disposed opening 35 having a threaded wall. The outer ends of the sections 18 and 19 are beveled as at 36. The side members are of like 10 construction, with this exception that the members 3, 8 are of greater length than the members 4, 7 and the members 5, 6 are of less length than members 4, 7. The members 3, 4 and 5 correspond in length to the length of 15 the members 8, 7 and 6 respectively. The construction of each of its side members is best shown in Figures 7 and 8 and each of which includes a central section 37, a pair of intermediate sections 38, 39 and a pair of end 20 sections 40, 41. The inner ends of sections 38, 39 are hinged as at 42, 43 to the ends of section 37, and the outer ends of sections 38, 39 are hinged as at 44, 45 to the inner ends of sections 40, 41. The sections 37, 38, 39, 40 and 25 41, when extended have lap joints therebetween, as the inner ends of sections 40, 41, both ends of sections 38, 39 and both ends of section 37 are provided with reduced apertured extensions as indicated at 46, Figure 10. 30 The apertures in said extensions register when the side member is extended, and extending through each pair of registering apertures is a removable latching device 47, see Figures 1 and 2. The outer end of section 40 and section 41 is enlarged as at 48, beveled as at 49 and apertured as at 50. The sections 38, 39 are apertured as at 51 and the section 37, as at 52.

The rib members 9, 10 and 11 are of like 40 construction, with this exception that the member 10 is of greater length than the members 9 and 11 and these latter correspond in length. The construction of the rib members is best shown in Figures 17, 18, and 19 and by reference thereto each rib member includes 45 a central section 53, a pair of end sections 54, 55 and two pairs of intermediate sections. The sections of one pair are indicated at 56, 57 and the sections of the other pair at 58, 59. 50 The ends of each of the sections 53, 56, 57, 58 and 59 are oppositely beveled. The inner ends of sections 54, 55 are beveled. The section 53 is hinged to sections 57, 58 as at 60, 61. The sections 56, 57 are hinged together as 55 at 62. The sections 58, 59 are hinged together as at 63. The inner ends of sections 54, 55 are hinged to the outer ends of sections 57, 59 as at 64, 65. Each of the sections 53, 54, 55, 56, 57, 58 and 59 is formed with a central opening 66. The hinge connections between the sections are countersunk. The sections 56, 57, 58 and 59 have enlarged ends to provide grooves 66' and the sections 54, 55 are mortised as at 66''.

65 Each tensioning member or element, best

shown in Figures 2 and 16, comprises a bar 67 of triangular cross section having a rounded lower end 68. The inner side of the bar 67 is formed with a socket 69 for the reception of an adjusting means 69' therefor in the 70 form of a threaded bolt which threadedly engages with the wall of opening 35 in an outer section of the keel member 2. The bars 67 oppose the outer sections of the keel member and are arranged within and engage the ends 75 of the body portion 2. See Figure 2. When the adjusting means 69' is operated to move outwardly the bars 67 are carried in the same direction and which applies tension to the body portion 1.

The side members 3 and 8 have attached to their inner faces spaced pins, eyes or hooks 71 which coat with lacing members 72, 73 for securing the body portion 1 to the frame. Lacing members 74, 75 are employed for connecting the flaps 14 and 15 together over the top at the bow and stern of the boat. The openings 16 and 17 in the body portion 1 are provided for the passage of the lacing members.

When the framing is set up the keel member 2 is first laid. The rib members are then mounted in the grooves of the keel member and secured to the latter by the removable holdfast devices 76. The side members are 95 positioned in the grooves and mortises of the rib members and detachably connected to the latter by removable holdfast devices 77. The sections 40, 41 of the side members are also mounted in the mortises of the sections 18, 19 of the keel member and detachably connected therewith by the removable holdfast devices 78. The bars 67 are arranged to oppose the sections 18, 19 of the keel member 2 and adjustably connected to said sections by the bolts 69. The body portion 1 is then laced to the framing and tensioned.

What I claim is:

1. A collapsible boat comprising a framing formed of a keel member formed of a series of hinged sections, a series of rib members seated in the keel member and formed of a series of hinged sections, a series of side members seating in the keel and rib members and formed of a series of hinged sections, 110 means for detachably connecting said sections together, a flexible body portion formed of impervious material, and means for detachably securing said body portion against the sides, ends and at the ends of the top of said frame.

2. A collapsible boat comprising a framing formed of a keel member formed of a series of hinged sections, a series of rib members seated in the keel member and formed of a series of hinged sections, a series of side members seating in the keel and rib members and formed of a series of hinged sections, means for detachably connecting said sections together, a flexible body portion formed of im- 125

- pervious material, means for detachably securing said body portion against the sides, ends and at the ends of the top of said frame, and tensioning means for said body portion 5 positioned at the ends of and exteriorly of the keel member and adjustably connected to the latter.
3. A collapsible boat comprising a framing 10 formed of a keel member formed of a series of hinged sections, a series of rib members seated in the keel member and formed of a series of hinged sections, a series of side members seating in the keel and rib members and formed of a series of hinged sections, means 15 for detachably connecting said sections together, a flexible body portion formed of impervious material, means for detachably securing said body portion against the sides, ends and at the ends of the top of said frame, 20 and means for latching the sections of each of said side members from movement when connected to the keel and rib members.

4. A collapsible boat comprising a framing 25 formed of a keel member formed of a series of hinged sections, a series of rib members seated in the keel member and formed of a series of hinged sections, a series of side members seating in the keel and rib members and formed of a series of hinged sections, means 30 for detachably connecting said sections together, a flexible body portion formed of impervious material, means for detachably securing said body portion against the sides, ends and at the ends of the top of said frame, tensioning means for said body portion positioned at the ends of and exteriorly of the 35 keel member and adjustably connected to the latter, and means for latching the sections of each of said side members from movement when connected to the keel and rib members. 40

In testimony whereof, I affix my signature hereto.

EERO V. LANGEN.
